(57) **CLAIM**

The ornamental design of a convertible crib as shown and described.

DESCRIPTION

FIG. 1 is a perspective view of a first embodiment of a convertible crib showing my new design;

FIG. 2 is a front elevational view of the first embodiment, with the rear elevational view being a mirror image thereof;

FIG. 3 is a right side elevational view of the first embodiment, with the left side view being a mirror image thereof;

FIG. 4 is a top plan view of the first embodiment;

FIG. 5 is a bottom plan view of the first embodiment;

FIG. 6 is an exploded view of the first embodiment showing the components separated;

FIG. 7 is a perspective view of a second embodiment of the convertible crib of this new design, shown in an alternate configuration;

FIG. 8 is a front elevational view of the second embodiment, with the rear elevational view being a mirror image thereof;

FIG. 9 is a right side elevational view of the second embodiment, with the left side elevational view being a mirror image thereof;

FIG. 10 is a top plan view of the second embodiment;

FIG. 11 is a bottom plan view of the second embodiment; and,

FIG. 12 is an exploded view of the second embodiment showing the components separated.

The two exploded views are provided to further clarify the relationship between the two embodiments, namely that they are identical except for the shorter length of the crib in the second embodiment. The difference in appearances results from the absence, in the second embodiment, of the 4 gap-panels between the upright posts and the end panels. The broken lines depict portions of the convertible crib and form no part of the claimed design.
